NICHOLAS S. VEDDER, OF TROY, NEW YORK.

Design No. 3,324, dated January 5, 1869.

DESIGN FOR THE BASE AND TOP OF A STOVE.

The Schedule referred to in these Letters Patent and making part of the same.

To all whom it may concern:

Be it known that I, NICHOLAS S. VEDDER, of the city of Troy, in the county of Rensselaer, and State of New York, have invented or produced a new and original Design for a Top and Base of a Stove, of which the following is a full and exact description, reference being had to the accompanying photographs, in which—

Figure 1 represents the top, and

Figure 2, the base of a stove having my said design.

My new design for the annular outside plate R of the top consists of the concentric series of ornaments and mouldings s t u, all shaped and disposed together, as represented in fig. 1.

The design for the circular central removable plate V of the top consists of the concentric series of mouldings and ornaments w x y, shaped and arranged as shown in fig. 1; and

My design for the plate Z of the base consists of the series of ornamentalations and mouldings a b c, shaped and disposed on the rising body of the plate, so as to present an appearance like that represented in fig. 2.

What I claim as my invention or production, and desire to secure by Letters Patent, is—

The design for the plates R and V of the top, and plate Z of the base of a stove, as herein described and represented.

In testimony whereof, I hereunto subscribe my name, this 8th day of December, 1868.

NICHOLAS S. VEDDER.
